FIG. - 2.

FIG. - 1.

INVENTOR.
Francis A. Jimerson.

BY *Robert H. Clegg*
HIS ATTORNEY.

UNITED STATES PATENT OFFICE

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY

ENGINE

Application filed October 19, 1927. Serial No. 227,190.

This invention relates to engines of the reciprocating piston type and more particularly to a cylindrical cross head guide for a double acting piston engine.

One object of the invention is to enable a connecting rod to be quickly disconnected from the cross head.

Another object is to provide a large bearing area for the cross head.

Other objects and advantages of the invention will be in part apparent and in part pointed out hereinafter.

In the drawings in which similar reference characters refer to similar parts,

Figure 1 is a longitudinal section through a portion of an engine or motor provided with a cross head guide constructed in accordance with the practice of the invention, and

Figure 2 is a longitudinal section along the line 2—2 of Figure 1 looking in the direction of the arrows.

Referring to the drawings, there is disclosed a type of tool commonly known as a close quarter drill to which the engine constructed in accordance with the practice of the invention is particularly adapted. The tool includes a casing A within which is suitably mounted a crank shaft B adapted to be actuated by the engine and having suitable anti-friction bearings C.

The engines includes a pair of cylinders D which may be cast integrally in a single block E and within which a pair of pistons F are adapted to reciprocate. The engine is preferably double acting, the pistons F being alternately exposed to compressed air or other suitable motive fluid on both front and rearward faces. One end of each cylinder D is closed by means of a head formed integrally with a cross head guide G having a stuffing box H extending into the cylinder and containing suitable packing material J compressed by a gland K. A piston rod L suitably attached as by means of a nut O to the piston F is formed with an integral cross head P which is cylindrical in form and adapted to slide in a cylindrical bore Q of the cross head guide G.

The cross head P is provided with a transverse bore R into which is inserted a pin S

for connecting a connecting rod T to the cross head P by means of which the power is transmitted from the piston F to the crank shaft B. To permit freedom of movement of the end of the connecting rod T, the cross head P is broached as shown at U.

In practice it often becomes desirable to remove the connecting rod T from the cross head P without taking the entire engine apart and to this end means are provided by which the pin S may be removed by merely disconnecting the crank shaft of the connecting rod from the crank shaft B. For this purpose the pin S is slidably mounted in the aperture R of the cross head P and apertures V are provided in the cross head guide G through which the pin S is adapted to be passed. In order that the pin S may normally stay in position, the apertures V are located preferably transversely to the plane in which the pin S normally lies. In order, therefore, to remove the pin S, it is merely necessary to rotate the cross head P through an angle, preferably 90°.

Access to the interior of the casing to disconnect the crank end of the connecting rod T is provided by a cover W suitably bolted to the casing and covering an aperture X. Preferably the apertures V are directed so that the pins S may be removed in the direction of the aperture X.

It is thought that the above description indicates the method of removing the connecting rod T when such is necessary, it being noted that with the cover plate W removed, the connecting rod T is disconnected from the crank shaft B by removing the cap screw Y whereupon the connecting rod T is rotated and the pin S is brought into registry with the apertures V. The pin S is readily removable through the apertures V and the connecting rod T withdrawn and removed through the apertures X.

This invention is not restricted to the specific form used for an illustration, but may be applied to any similar construction where a reciprocating member is connected to a connecting rod by means of a pin, access to which may be desirable through the walls of the cylinder. Although in the instance illus-

trated the pin is held in place by turning the reciprocating member in its bore, other means of retaining the pin in position may be adopted.

In this instance the pistons F are double acting, the cylinders D being provided with suitable ports (not shown) and a valve (not shown) preferably driven by a counter-shaft Z.

Thus are accomplished among others the objects hereinbefore recited.

I claim:

1. A cross head mechanism comprising a cylindrical cross head guide, a cylindrical cross head slidable in said guide and a pin in the cross head adapted to be attached to a connecting rod, said guide having an aperture extending therethrough transverse to the normal position of said pin, said cross head being rotatable in the guide to align the pin with the aperture to permit removal of said pin without removal of the cross head.
2. In an engine and the like the combination of a cylindrical bore and a reciprocating member therein, a connecting rod for the reciprocating member, means to pivotally connect the rod to the reciprocating member, the wall of said cylindrical bore having an opening to permit access to the connecting means.
3. In an engine and the like the combination of a cylindrical chamber and a reciprocating member therein, a connecting rod, a pin to connect the rod to the reciprocating member, the wall of the cylindrical chamber having an opening to permit removal of the pin.
4. In an engine and the like the combination of a cylindrical chamber and a reciprocating member therein, a connecting rod, a wrist pin for connecting the rod to the reciprocating member, the wall of the cylindrical chamber having diametrically opposed openings to permit removal of the wrist pin.
5. In an engine and the like the combination of a cylinder and a piston therein, a connecting rod, a wrist pin for connecting the rod to the piston, said cylinder having diametrically opposed apertures in its wall to permit removal of the wrist pin.
6. In an engine and the like the combination of a cylinder and a piston therein, a connecting rod, a wrist pin for connecting the rod to the piston, and an aperture in the wall of the cylinder to permit access to the wrist pin.
7. In an engine and the like the combination of a cylinder and a piston therein, a connecting rod, a wrist pin for connecting the rod to the piston, and an aperture in the wall of the cylinder to permit access to the wrist pin when the piston occupies a position near bottom center.

In testimony whereof I have signed this specification.

FRANCIS A. JIMERSON.
